UNITED STATES PATENT OFFICE.

SAMUEL D. SMITH, OF EAST DEDHAM, MASSACHUSETTS, ASSIGNOR OF ONE-HALF TO
JOHN C. KENNEDY, OF BOSTON, MASSACHUSETTS.

CUSHION-HEEL.

1,131,568.

Specification of Letters Patent.

Patented Mar. 9, 1915.

Application filed September 21, 1914. Serial No. 862,728.

To all whom it may concern:

Be it known that I, SAMUEL D. SMITH, of East Dedham, in the county of Norfolk and State of Massachusetts, have invented 5 certain new and useful Improvements in Cushion-Heels, of which the following is a specification.

This invention relates to cushion heels or heel treads of the kind usually known as rubber heels. Such heels are in great demand in spite of their lack of durability. Attempts have been made to increase their 15 wearing qualities but, so far as I am aware, all such attempts have either impaired the resilience of the heels or have resulted in the leaving of cavities which soon get packed with dirt.

The object of my invention is to provide a cushion heel having wear-resisting plugs in those portions of the tread surface which are usually first worn down, the plugs being of a form which present solid wear surfaces that wear well and prevent the picking up of dirt, the whole being so constructed that the elasticity of the heel is not lessened by the presence of the plugs.

As so far described, the object is substantially the same as explained in my Patent 1,114,302, October 20, 1914. I have found, however, that it is further desirable to provide means for more positively anchoring the plugs so that they cannot work laterally out of the body of the heel. This is more particularly desirable when the plugs 35 are located very close to the margin of the heel.

Therefore, a further object of my present invention is to provide means for preventing lateral or outward movement of the 40 plugs, while still permitting said plugs to yield vertically when the heel is in use.

To these ends my invention consists in the improved cushion heel or tread which I shall now proceed to describe and claim.

45 Of the accompanying drawings, Figure 1 is a bottom view of an elastic heel or tread embodying my invention, the anchor being indicated by dotted lines. Fig. 2 represents a section on line 2—2 of Fig. 1, on a larger scale. Fig. 3 is a plan view of a series of plugs connected with a single anchor device. Fig. 4 is a plan view of the anchor. Figs.

2, 3 and 4 are all on the same enlarged scale. Figs. 5, 6, 7, 8 and 9 are detail views of modified forms of anchors.

55

Referring first to Figs. 1, 2, 3 and 4 the body 12 of the tread, composed of rubber or any of the compositions used for elastic or cushion heels or heel-treads, is shown as formed with holes 13 as usual for the nails 60 which secure the said body to the heel portion of a shoe, or to leather heel-lifts. Such holes may extend entirely or but partially through the body. They constitute no part of this invention. In fact the body may be 65 secured in place by any suitable means. At the rear of the heel, which is the portion that first shows wear, is a row of wear-resisting plugs having solid heads 14 substantially flush with the tread surface. The 70 shanks 15 of the plugs are preferably also solid a portion of their length. The inner end of each plug is flanged as at 16, and the head is of greater diameter than the shank to form a flange 17 which is preferably of 75 greater diameter than the flange 16. In alinement with the cavity 18 of the plug, the body is formed with a hole or recess 19 extending to the upper surface of the body.

In the manufacture of the article, the 80 plugs are supported by pins rising from the bottom of a mold, said pins fitting the cavities 18 of the plugs which then of course, present their heads 14 upwardly, the material of the body is then caused to fill 85 the mold and to enter the spaces around the shanks between the flanges 16, 17 and then vulcanized. When the article is removed from the mold, the holes 19 are the result of the presence in the mold of the plug-supporting pins mentioned. These holes 19, 90 however, are deliberately formed in the body 12 to perform the service, when the article is in use, of reducing the solidity of the elastic substance above the plugs, to permit the plugs to yield more readily when the user is walking than they could if the body were solid above the plugs. In other words, the holes 19 compensate for hardness of the plugs so that the elasticity of the heel 95 is not impaired by the plugs. Of course, when the body is secured in place so tightly that no air can escape from the holes 19, the confined air causes an additional cushioning

100

effect. No air can escape around the plugs owing to the flanges 16, 17, and the material of the body which is packed between said flanges. Both flanges act to prevent the plug from being forced up into the hole 19. When the weight of the wearer causes the material of the body to be compressed, tending to force the plugs into the body, the fact that the flange 17 is larger than the flange 16 causes the material of the body to be pressed more firmly in between the two flanges.

It will readily be understood that if the plugs are embedded in the body close to the margin of the latter, there might be some liability of the plugs being pulled out, especially after the heel has been worn for some time. The anchorage illustrated in Figs. 1, 2, 3 and 4 consists of a plate 20 having apertures 21 sufficiently larger than the diameter of the shanks 15 of the wear studs to enable the studs to slide through said apertures. In order to assemble these studs of the type illustrated, with an anchorage of this form, said plate is preferably provided with larger apertures which communicate with the guiding apertures 21 by means of throats 22. The plugs may be inserted through the larger apertures and then slid along the throats 22 to the guiding apertures 21, said throats 22 being preferably of such width that the shanks of the studs will have to be pushed along with some force. This is in order that when the series of plugs have been placed in the guiding apertures 21, the plate 20, with the entire series of plugs, may be picked up as a unit and placed properly in the mold. When the molding is done, some of the rubber will not pass into the large apertures and also the throats 22 of the plate so that said plate is retained in place. However, a hole such as indicated at 23 may be employed in such position as to be in alignment with one of the holes 13 of the body 12 so that an attaching nail passed therethrough will positively hold the plate against edgewise movement.

As shown in Fig. 5 the anchorage may comprise a piece of wire 20^a bent as indicated to provide guiding apertures for the shanks 15 of the studs. When the anchorage is of this construction, the sides of the loops of the wire which hold the shanks 15 may be curved inwardly somewhat so that the studs can be slid or snapped to the position indicated in Fig. 5 when the studs are being assembled with the anchorage.

Instead of providing a single anchorage for a series of studs, I may provide a single strip such as indicated at 20^b in Figs. 6 and 7, said strip being bent at one end to be engaged with the body and having an aperture at its other end through which the shank 15^a of a stud, having a head 14^a may be inserted, the other end of the shank 15^a

being then headed over in any well-known manner.

The wear stud may be integral with the anchor as indicated in Fig. 8 which illustrates a piece of metal having an anchor portion 20^c and a wear stud portion 14^c. This form may possess a single portion 14^c for each strip portion 20^c as indicated in Fig. 8, or, as indicated in Fig. 9, a piece of sheet metal may be formed to present an anchorage 20^d, said piece being slotted to form tongues which are then bent over to provide wear stud heads 14^d. The hole or holes 13^d may either receive some of the rubber when the article is being molded, or one or more attaching nails may be driven through such holes.

When either of the forms shown in Figs. 5, 6, 7, 8, and 9 is employed, it is, of course, so located in the body 12 that the wear-resisting members 14, 14^a, 14^c, or 14^d will be located in the lower ends of the holes 19, in substantially the position occupied by the wear-resisting members 14 illustrated in Figs. 1 and 2.

It is to be understood that with each of the forms of anchors employed, the method of assembling them with the rubber material in the manufacture of the completed heels will preferably be as hereinbefore described. Each form provides means for preventing outward movement of the wear head or stud and keeps the latter in line with the hole 19 for the purpose hereinbefore described.

I am aware that tubular wear-pieces, open at their outer ends, have been embedded in rubber heels, said pieces also serving as washers for heel-attaching nails, but such devices pick up dirt and mar carpets and polished floors, and impair the resilience of the rubber. I am also aware that it has been proposed to provide leather soles with holes and fill or partially fill the holes with solid plugs, but such plugs do not yield because the leather is not sufficiently elastic. And I am also aware that solid plugs have been embedded in rubber soles and heels, the plugs extending entirely through from one surface to the other of the rubber. Obviously this entirely destroys any cushioning effect of the rubber. I do not claim any of these ideas as within my invention.

What I claim is:

1. A cushion heel having an anchorage member embedded therein, said member having a series of guiding apertures in a curved row, and a series of wear-resisting members having shank portions slidably engaged in said apertures.

2. A cushion heel comprising an elastic body having holes extending upwardly from its tread surface, a wear-resisting member secured in the lower end of each hole and having a length less than the depth of said

holes to permit the heel to be compressed without lessening the cushioning effect by the plugs, and anchoring means for preventing outward displacement of said members, said anchoring means extending in a direction away from the margin of the heel and embedded in the elastic body.

3. A cushion heel having holes extending upwardly from its tread surface, a wear-resisting member secured in the lower end of each hole and having a length less than the depth of said holes to permit the heel to be compressed without lessening the cushioning effect by the plugs, and an anchoring member for preventing outward displacement of said wear-resisting members, said latter members being loosely connected with the anchoring member to permit them to

move vertically independently of the anchoring member.

4. A cushion heel comprising an elastic body having a plurality of wear-resisting members near its margin, and a single anchoring member connecting and extending inwardly from said members for preventing lateral displacement of said members, said anchoring member being embedded in the elastic body between its upper and lower surfaces.

In testimony whereof I have affixed my signature, in presence of two witnesses.

SAMUEL D. SMITH.
